W. L. R. EMMET

ELASTIC FLUID TURBINE

Filed Oct. 20, 1921

Inventor:
William L.R. Emmet,
by *Alfred S. Davis*
His Attorney.

UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

ELASTIC-FLUID TURBINE.

Application filed October 20, 1921. Serial No. 509,096.

To all whom it may concern:

Be it known that I, WILLIAM L. R. EMMET, a citizen of the United States, residing at Schenectady, county of Schenectady, State of New York, have invented certain new and useful Improvements in Elastic-Fluid Turbines, of which the following is a specification.

The present invention relates to elastic-
10 fluid turbines and has for its object to pro-
vide an improved valve gear for regulating
and controlling the admission of elastic fluid
to the turbine.

For a consideration of what I believe to
15 be novel and my invention, attention is di-
rected to the accompanying description and
the claims appended thereto.

In the drawing, the figure is a diagram-
matic view of a turbine equipped with a
20 valve gear embodying my invention.

Referring to the drawing, 5 indicates the
casing of an elastic-fluid turbine and 6 the
shaft, the latter being mounted in suitable
bearings, one of which is indicated at 7.
25 The turbine may be of any suitable struc-
ture and type and is indicated in the draw-
ing in diagrammatic manner only. Mounted
on casing 5 of the turbine is a valve
30 chest 8 in which is located a series of valves
which controls the admission of elastic fluid
to the turbine. The stems of the valves pro-
ject out through the top of casing 5 and as-
sociated with each stem is a spring 9 which
35 acts to bias the valve to closed position.

The valves are arranged to be opened suc-
cessively by means of cams 10 carried by a
shaft 11 mounted in bearings 12 on the valve
chest. As shaft 11 turns in one direction
40 the cams act to successively open the valves
and as it turns in the other direction it re-
leases the valves to permit them to close one
after another. This type of valve mecha-
nism is one in common use and well known
45 to the art. It is illustrated only in a gen-
eral way and is to be taken as typical of any
suitable valve mechanism for regulating the
admission of elastic fluid. On the end of
cam shaft 11 is a pinion 13 which meshes
50 with a rack on the upper end of a rod 14.
The lower end of rod 14 is connected to a
piston 15 which moves in cylinder 16 and
forms a fluid actuated motor for turning
the cam shaft. Admission of actuating

fluid to the motor is controlled by a pilot
valve 17 of usual construction, 18 being the 55
inlet conduit and 19 and 19^a the discharge
conduits. The stem 20 of the pilot valve is
connected to one end of a lever 21, the
other end of the lever being connected to the
upper end of rod 22, the lower end of which
60 is carried by a piston 23 which moves in a
cylinder 24. Piston 23 is biased to a posi-
tion toward the top of cylinder 24 by a
spring 25 and its downward movement is
limited by a suitable stop 26. The central
65 portion of lever 21 is connected by a link 27
to the central portion of a lever 28, the
right-hand end of lever 28 being connected
by a rod 29 to the end of the governor lever
30 of a governor 31 which may be of any
70 suitable structure and which is driven in ac-
cordance with the speed of the turbine to
raise and lower governor lever 30. The gov-
ernor 31 is shown only in outline since its
detail structure forms no part of the pres-
75 ent invention.

The left-hand end of lever 28 is connected
by a link 32 to the central portion of a lever
33. One end of lever 33 is pivoted to an
arm 34 fixed to rod 14 and the other end is
80 connected by a rod 35, bell crank lever 36,
rod 37, bell crank lever 38 and rod 39 to the
hand lever 40 which is adapted to be ad-
justed along a toothed quadrant 41.

Elastic fluid is admitted to chest 8 by a
conduit 42 in which is a combined trip and
throttle valve 43 of any suitable type. A
standard and well known type of combine-
d trip and throttle valve is illustrated, the
valve being adapted to be opened and closed
90 manually by means of hand wheel 44 and to
be automatically closed whenever the rod 45
which is connected to arm 46 of the valve
structure moves toward the right, i. e., in the
direction of the arrow. Rod 45 is connect-
95 ed at its right-hand end to an arm 48 fixed
on a shaft 49. On shaft 49 is fixed a sec-
ond arm 50 which at its free end is pivoted
to a rod 51 which projects down through a
casing 52. The lower end of rod 51 is
100 adapted to be supported on a trip finger 53
pivoted on a shaft 54. The lower end of
trip finger 53 terminates in a nose 55 which
stands in proximity to an emergency gov-
ernor ring 56 carried by shaft 6. The emer-
gency governor ring is normally held con-

2

centric to the shaft 6 but in case of excessive speed it assumes an eccentric position so as to strike nose 55 of trip finger 53 knocking it from under the rod 51. This 5 type of emergency governor mechanism is one well known in the art and is to be taken as typical of any suitable emergency governor adapted to come into play in case of excess speed. The trip finger normally 10 stands under rod 51 as shown in the drawing and is biased to this position by a spring 57, movement of the trip finger being limited by a stop pin 58. On rod 51 inside casing 52 is fixed a collar 59 and surrounding rod 51 between collar 59 and the top of casing 52 is a spring 60 which acts to force rod 51 downward whenever it is released from engagement with trip finger 53. Rod 51 projects beyond arm 50 and at its upper 15 end is pivoted to one end of a lever 61. Lever 61 is pivoted at an intermediate point on a fixed fulcrum 62 and at its other end is connected to the upper end of stem 63 carried by a valve 64 which slides in a valve 20 casing 65 and is adapted to cover and uncover two ports 66 and 67, both of which communicate with a chamber 68 at the side of valve casing 65. Chamber 68 is connected by a pipe 69 to the upper end of cylinder 25 30 35 40 45 50 55 60 65 70 75 80 85 90 95 100 105 110 115 120 125 130 135 140 145 150 155 160 165 170 175 180 185 190 195 200 205 opened in advance of the valve mechanism in chest 8 and closed subsequent to the closing of such valve mechanism.

The operation is as follows: The drawing shows the parts when the turbine is running under normal conditions. Combined trip and emergency valve 43 is open and one or more of the control valves in chest 8 are open, or may be, according to the load on the turbine. Valves 74 and 75 in conduit 72 are also open. Rod 51 is supported in raised position on trip finger 53 and holds the catch for trip valve 43 in engaging position, the catch 80 for valve 74 in engaging position, and valve 64 over the port 66 in casing 65, port 67 being uncovered. Elastic fluid pressure from the lubricating system is admitted through pipe 70 to valve casing 65 through port 67, chamber 68, and pipe 69 to the upper end of cylinder 24. This pressure, acting on the upper side of piston 23, serves to hold it down against stop 26, spring 25 being held under compression. Piston 23 forms a movable abutment which is normally held stationary to provide a fixed fulcrum for lever 21. In case of increase in speed, governor 31 will lower the right-hand end of governor lever 30 thereby lowering pilot valve 17 through the intermediary of rod 29, lever 28, link 27, and lever 21. During this movement the left-hand end of lever 28 pivots on the lower end of link 32 which is stationary and the left-hand end of lever 21 pivots on the upper end of rod 22 which is also stationary. When pilot valve 17 is lowered actuating fluid will be admitted through pipe 18 to cylinder 16 below piston 15 forcing piston 15 upwards. The fluid above piston 15 escapes through pipe 19 at the top of the pilot valve. This forces piston 15 upward thereby raising the rack carried by rod 14 and turning shaft 11 in a direction to shut off one or more of the valves in valve chest 8 which results in admitting less elastic fluid to the turbine and hence it will decrease in speed. When rod 14 moves upward lever 33 is turned on the upper end of rod 35 as a pivot. This results in lifting the left-hand end of floating lever 28 which serves to raise the pilot valve to again cover the ports which regulate the flow of motive fluid to and from cylinder 16. These connections serve therefore as a usual form of follow-up device. In case of decrease in speed the speed governor will raise the right-hand end of governor lever 30 which will actuate the pilot valve in a direction opposite to that just described resulting in opening a valve or valves in valve chest 8 to admit more elastic fluid to the turbine. It will thus be seen that during normal operation, while the turbine is under the control of the speed governor, the fluid pressure on the upper side of piston 23 holds it in downward position.

tion and provides a fixed fulcrum for the left-hand end of lever 21. By means of hand lever 40 the operator can raise and lower the pilot valve through the intermediary of rod 39, bell crank lever 38, rod 37, bell crank lever 36, rod 35, lever 33, link 32, floating lever 28, link 27 and lever 21 to manually vary the speed of the turbine.

In case of excess speed emergency governor 56 will strike trip finger 53 knocking it from under rod 51 whereupon spring 60 will force rod 51 downward turning the shaft 49. When shaft 49 turns rod 45 will be pulled toward the right thereby tripping emergency valve 43 which will automatically close. At the same time arm 83 will pull down on rod 82 releasing catch 80 from engagement with valve 74 which will be closed by spring 77 to shut off the admission of low pressure elastic fluid to the turbine. Also valve 64 in casing 65 will be raised by lever 61, uncovering port 66 and covering port 67. When port 67 is covered the admission of fluid pressure to chamber 68 is cut off, while the uncovering of port 66 connects such chamber to discharge pipe 71. The fluid pressure above piston 23 is thus relieved through pipe 69, chamber 68 and port 66 to discharge pipe 71 whereupon spring 25 will force piston 23 toward the top of cylinder 24. This movement of piston 23 turns lever 21 on the lower end of link 27 thereby lowering the pilot valve, i. e., reversing its position, which will admit motive fluid to cylinder 16 below piston 15 whereupon the piston 15 will be raised to close the controlling valves in valve casing 8. Fluid above the piston escapes by way of discharge pipe 19 which is connected to the upper end of the pilot valve casing. This will also result in closing valve 75 in conduit 72.

It will thus be seen that when the emergency mechanism comes into play, not only are the emergency valves 43 and 74 closed, but also the controlling valve mechanism in valve chest 8 and the controlling valve 75. If at any time during the operation of the turbine the pressure of the lubricating system should fail spring 25 will immediately force piston 23 up in cylinder 26 to reverse the position of pilot valve 17 and effect the closing of the controlling valve mechanism contained in valve chest 8 and valve 75.

In accordance with the provisions of the patent statutes, I have described the principle of operation of my invention, together with the apparatus which I now consider to represent the best embodiment thereof; but I desire to have it understood that the apparatus shown is only illustrative, and that the invention may be carried out by other means.

What I claim as new and desire to secure by Letters Patent of the United States, is,—

1. The combination with a prime mover

having a conduit for the admission of elastic fluid, an emergency valve mechanism and a controlling valve mechanism arranged in series in said conduit, and means including a fluid actuated motor having a pilot valve for positioning the controlling valve mechanism, of an emergency governor, and means operated by it for tripping the emergency valve mechanism and moving the pilot valve to effect the closing of the controlling valve 75 mechanism.

2. The combination with a prime mover having a conduit for the admission of elastic fluid, an emergency valve mechanism and a controlling valve mechanism arranged in series in said conduit, a speed governor, and a servo-motor comprising a pilot valve through which the speed governor actuates the controlling valve mechanism, of an emergency governor, and means operated by it for effecting the closing of both valve mechanisms.

3. The combination with a prime mover having a conduit for the admission of elastic fluid, an emergency valve mechanism and a controlling valve mechanism arranged in series in said conduit, a speed governor, and a servo-motor comprising a pilot valve through which the speed governor actuates the controlling valve mechanism, of an emergency governor, and means operated by it to simultaneously trip the emergency valve mechanism and move the pilot valve to effect the closing of the controlling valve mechanism.

4. In combination, a prime mover, a conduit for supplying elastic fluid thereto, a plurality of valve means in said conduit one of which is a control valve means, a speed governor for regulating the control valve means, means for holding another of said valve means open, and emergency governor mechanism for effecting the simultaneous closing of all said valve means in case of excess speed.

5. A valve gear for a prime mover comprising a control valve mechanism and an emergency valve mechanism arranged in series, speed responsive means for positioning the control valve mechanism, and an emergency governor for the emergency valve mechanism, characterized by the fact that the emergency governor is connected to the control valve mechanism in such manner that whenever it operates to close the emergency valve mechanism it closes also the control valve mechanism.

6. The combination with a prime mover, of a valve mechanism controlling the admission of motive fluid thereto, a lever through which the valve mechanism is actuated, a movable abutment which presents a stationary fulcrum for the lever, governor mechanism for moving the lever about such fulcrum to open and close the valve mechanism,

means for supplying fluid pressure to said abutment, and means for controlling the fluid pressure supplied to the abutment.

7. The combination with a prime mover, of a valve mechanism controlling the admission of motive fluid thereto, a lever through which the valve mechanism is actuated, a movable abutment which presents a stationary fulcrum for the lever, governor mechanism for moving the lever about such fulcrum to open and close the valve mechanism, means for supplying fluid pressure to said abutment, a valve for controlling the supply of fluid pressure to the abutment, and means responsive to an abnormal operating condition of the prime mover for actuating said valve.

8. The combination with a prime mover, of a valve mechanism controlling the admission of motive fluid thereto, a lever through which the valve mechanism is actuated, a movable abutment which presents a stationary fulcrum for the lever, governor mechanism for moving the lever about such fulcrum to open and close the valve mechanism, a conduit connected to the abutment, a valve structure for connecting said conduit to a supply of fluid pressure or to a region of lower pressure, and an emergency governor mechanism for actuating said valve structure.

9. The combination with a prime mover, of an emergency valve mechanism, a controlling valve mechanism, a governor, a lever moved by the governor for effecting the opening and closing of the controlling valve mechanism, a movable member which presents a fixed fulcrum for said lever, an emergency governor, and means actuated by the emergency governor for tripping the emergency valve mechanism and releasing said member.

10. The combination with a prime mover, of an emergency valve mechanism, a controlling valve mechanism, a governor, a lever moved by the governor for effecting the opening and closing of the controlling valve mechanism, a movable abutment which presents a fixed fulcrum for said lever, a conduit for supplying fluid pressure to said abutment, a valve structure in said conduit, an emergency governor, and means actuated by the emergency governor for tripping the emergency valve and actuating said valve structure to effect movement of said abutment for closing the controlling valve mechanism.

11. In combination, a prime mover, a conduit for supplying elastic fluid thereto, an emergency valve mechanism and a control valve mechanism in said conduit, said emergency valve mechanism being biased to closed position, means for holding the emergency valve mechanism open, means for ef-

fecting the closing of the control valve mechanism, and mechanism which when actuated operates both said means.

12. In combination, a prime mover, a conduit for supplying elastic fluid thereto, an emergency valve mechanism and a control valve mechanism in said conduit, said emergency valve mechanism being biased to closed position, means for holding the emergency valve mechanism open, means for effecting the closing of the control valve mechanism and mechanism responsive to an abnormal operating condition for operating both said means.

13. In combination, a prime mover, a conduit for supplying elastic fluid thereto, an emergency valve mechanism and a control valve mechanism in said conduit, said emergency valve mechanism being biased to closed position, means for holding the emergency valve mechanism open, means for effecting the closing of the control valve mechanism, an emergency speed governor, and mechanism operated by the emergency speed governor for releasing said holding means and actuating the means for effecting the closing of the control valve mechanism.

14. In combination, a prime mover, a conduit for supplying elastic fluid thereto, valve mechanism in said conduit, a servomotor comprising a pilot valve for actuating the valve mechanism, a governor, a lever through which the governor actuates the pilot valve, means providing a fixed fulcrum for said lever, means for releasing said fulcrum, and means which when the fulcrum is released operates said lever independently of the governor to move the pilot valve in a direction to effect the closing of the valve mechanism.

15. In combination, a prime mover, a conduit for supplying elastic fluid thereto, valve mechanism in said conduit, means including a governor, a servomotor, and a lever for actuating the valve mechanism, a movable abutment on which said lever pivots, a conduit for supplying fluid pressure to said abutment, a valve in said conduit, and emergency governor mechanism for actuating said valve.

16. In combination, a prime mover, a conduit for supplying elastic fluid thereto, valve mechanism in said conduit, means including a governor, a servomotor and a lever for actuating the valve mechanism, a movable abutment on which said lever pivots, a conduit for supplying elastic fluid pressure from the lubricating system for the prime mover to said abutment, a valve in said last named conduit, and means for actuating it.

In witness whereof, I have hereunto set my hand this 19th day of October, 1921.

WILLIAM L. R. EMMET.
